Patented Dec. 31, 1974

234,032

SUCTION NEEDLE FOR EAR OPERATIONS

Ricardo J. Heros, Memphis, Tenn., assignor to Richards
Manufacturing Co., Memphis, Tenn.

Filed Sept. 15, 1972, Ser. No. 289,678

Term of patent 7 years

Int. Cl. D24—02

U.S. Cl. D83—12 R

FIG. 1

FIG. 2

FIG. 3

FIG. 4

FIG. 5

FIG. 6

FIG. 7

FIG. 8

FIG. 1 is a top plan view of the suction needle for ear operations showing my new design;

FIG. 2 is a side elevational view thereof;

FIG. 3 is a bottom plan view thereof;

FIG. 4 is a side elevational view thereof showing the opposite side from that of FIG. 2 and showing the suction needle turned 180° about its longitudinal axis from that shown in FIG. 2.

FIG. 5 is an end elevational view thereof;

FIG. 6 is an end elevational view thereof from the opposite end of that shown in FIG. 5;

FIG. 7 is a sectional view taken as on the line VII—VII of FIG. 2; and

FIG. 8 is an enlarged fragmentary top plan view, broken away for ease of illustration.

I claim:

The ornamental design for a suction needle for ear operations, as shown.
